Attorney.

UNITED STATES PATENT OFFICE.

MAT BACEKOVICH, OF SABRATON, WEST VIRGINIA, ASSIGNOR OF ONE-HALF TO MATT SIKUTRICK, OF MONA, WEST VIRGINIA.

RAIL JOINT.

Application filed January 3, 1924. Serial No. 684,218.

To all whom it may concern:

Be it known that I, MAT BACEKOVICH, a citizen of Yugoslavia, residing at Sabraton, in the county of Monongalia and State of West Virginia, have invented certain new and useful Improvements in Rail Joints, of which the following is a specification.

This invention relates to certain new and useful improvements in rail joints and has for its primary object to provide a special type of joint chair wherein the adjacent ends of the meeting rail webs and base flanges are cut away and spaced from each other by the provision of an intervening integral block carried by the joint chair with the heads of the adjacent ends of the rails supported upon the upper side of the block.

With the above general objects in view and others that will become apparent as the nature of the invention is better understood, the same consists of the novel form, combination and arrangement of parts hereinafter more fully described, shown in the accompanying drawing and claimed.

In the drawing, wherein like reference characters designate corresponding parts throughout the several views,

Figure 1 is a side elevational view of a rail joint constructed in accordance with the present invention,

Figure 2 is a top plan view of the same showing the removable splice bar bolted in position,

Figure 3 is a top plan view of the joint chair,

Figure 4 is a vertical cross-sectional view taken on line IV—IV of Fig. 1,

Figure 5 is a vertical cross-sectional view taken on line V—V of Fig. 1 showing the head of the rail bolted to the chair block,

Fig. 6 is a detail sectional view taken on line VI—VI of Fig. 1, showing the interlocking connection between the removable splice bar and the joint chair, and

Figure 7 is a perspective view of the removable splice bar.

Referring more in detail to the accompanying drawing, the reference numerals 1 designate the meeting ends of rails supported in a joint chair, each rail embodying a tread 2, web 3 and a base 4. The ends of the web and base portion 4 of each rail are cut away as at 5 to provide an overhanging tread portion 2^a.

The joint chair includes a base plate 8 carrying one integral splice bar 9 of a length to extend over the meeting ends of the rails 1 and a second integral splice bar section 10 of a length to extend over the end of one of the rails. The base plate 8 and integral splice bars 9 and 10 carry an integral intermediate block 11 that spaces the adjacent ends of the rail webs and base flanges 3 and 4 with the overhanging portions 2^a of the rail treads supported on the upper side of the block 11 as illustrated. The base plate 8 opposite the end of the splice bar 9 spaced from the short splice bar section 10 carries an undercut flange 12 to receive the removable splice bar 13 having a beveled lower edge 14 interlocked with the undercut flange 12 while the forward end of the vertical portion of the splice bar 13 is beveled as at 15 to be received in the cutaway portion 16 of the block 11.

One of the rails 1 is positioned between the integral splice bars 9 and 10 while the other rail end may be laterally positioned adjacent the single splice bar 9 with the webs and base flanges of the meeting rail ends abutting the opposite sides of the central block 11 and with the rail tread portions 2^a overlying the block as illustrated in Figs. 1 and 2. The removable splice bar section 13 is then placed in position as shown in Fig. 4 and the meeting rail ends are anchored in the joint chair by the cross pins 17 passing through threaded openings 18 in the splice bar 13 and engaging the adjacent rail web. The joint chair is secured to the tie 19 by fastening devices passing through openings 20 in the base plate 8, and a further anchoring means for the joint chair includes the pins 21 passing downwardly through openings 22 provided in the block 11 as shown in Figs. 3, 5 and 6, the pins being driven downwardly into the supporting tie 19 so that the upper ends of the pins are substantially flush with the upper surface of the block 11. With the chair anchored in position as shown in Fig. 5, the projecting tread portions 2^a of the rails overlie and are supported on the block when the rails are positioned in the chair to protect the anchoring pins 21.

While there is herein shown and described the preferred embodiment of the present invention, it is nevertheless to be

understood that minor changes may be made therein without departing from the spirit and scope of the invention as claimed.

What is claimed as new is:—

- 5 1. In a rail joint of the class described, meeting rail ends, a joint chair supporting the same, integral splice bars and a removable splice bar section cooperating with the chair and rail ends, the removable splice bar section having an interlocking connection with the joint chair, and a central block intermediate the ends of one of the integral splice bars with which the removable splice bar is engaged.
- 10 10 2. In a rail joint of the class described, meeting rail ends, a joint chair supporting the same, integral splice bars and a removable splice bar section cooperating with the chair and rail ends, the removable splice bar section having an interlocking connection with the joint chair, a central block intermediate the ends of one of the integral splice bars with which the removable splice bar is engaged, and the web and base portions of the rail ends being cut away to provide overhanging tread portions supported on the block.
- 15 20 3. In a rail joint of the class described, meeting rail ends, a joint chair supporting the same, integral splice bars and a removable splice bar section cooperating with the chair and rail ends, the removable splice bar section having an interlocking connection with the joint chair, a central block intermediate the ends of one of the integral splice bars with which the removable splice bar is engaged, the web and base portions of the rail ends being cut away to provide overhanging tread portions supported on the block.
- 25 30 4. In a rail joint of the class described, meeting rail ends, a joint chair supporting the same, integral splice bars and a removable splice bar section cooperating with the chair and rail ends, the removable splice

bar section having an interlocking connection with the joint chair, a central block intermediate the ends of one of the integral splice bars with which the removable splice bar is engaged, the web and base portions of the rail ends being cut away to provide overhanging tread portions supported on the block, and fastening pins passing downwardly through the block and beneath the overhanging tread portions and entering the supporting tie for the rail.

4. In a rail joint of the class described, meeting rail ends, a joint chair supporting the same, integral splice bars and a removable splice bar section cooperating with the chair and rail ends, the removable splice bar section having an interlocking connection with the joint chair, a central block intermediate the ends of one of the integral splice bars with which the removable splice bar is engaged, the web and base portions of the rail ends being cut away to provide overhanging tread portions supported on the block, said block having perpendicular openings therein, and anchoring means for the chair including pins inserted in the block openings and driven in a supporting tie with the upper ends of the pins substantially flush with the upper surface of the block.

In testimony whereof I affix by signature.
MAT BACEKOVICH.
